UNITED STATES PATENT OFFICE.

ISADOR RUDOLPH, OF PHILADELPHIA, PENNSYLVANIA.

DESIGN FOR A RADIOCABINET OR SIMILAR ARTICLE.

Application filed December 6, 1924. Serial No. 11,604. Term of patent 7 years.

To all whom it may concern:

Be it known that I, ISADOR RUDOLPH, a citizen of the United States, residing at Philadelphia, in the county of Philadelphia and State of Pennsylvania, have invented a new, original, and ornamental Design for Radiocabinet or Similar Article, of which the following is a specification, reference being had to the accompanying drawing, forming a part thereof.

The figure is a perspective view of a cabinet showing my new design.

I claim:

The ornamental design for a radiocabinet or similar article as shown.

ISADOR RUDOLPH.

Witnesses:

CHAS. E. POTTS,
ELIZABETH GARBE.
